UNITED STATES PATENT OFFICE.

FRANK S. HARRINGTON, OF SLOATSBURG, NEW YORK.

RAILROAD SPIKE.

Application filed March 27, 1924. Serial No. 702,370.

To all whom it may concern:

Be it known that I, FRANK S. HARRINGTON, a citizen of the United States, and a resident of Sloatsburg, in the county of 5 Rockland and State of New York, have invented a new and Improved Railroad Spike, of which the following is a full, clear, and exact description.

This invention relates to a new and improved form of railroad spike, and has for 10 an object the provision of a simple and efficient spike which is provided with means whereby when driven into a railroad tie it will enter in the manner of a screw and, in 15 a corresponding manner, will be more difficult to be removed, either by the action of the trains on the rails or by reason of any deliberate force applied thereto.

Another object concerns the provision of 20 means on a spike for preventing its removal from a tie, such means being very readily incorporated in the spike in a simple and economical manner whereby these spikes can be produced at a low cost.

25 The invention is illustrated in the drawings, of which—

Figure 1 is an elevation of the spike;

Fig. 2 is a similar elevation taken at right angles to Fig. 1;

30 Fig. 3 is a plan view of a modified form of spike; and

Fig. 4 is a partial elevation of the modified form.

The forms of the invention shown in the 35 drawings are preferred forms, although it is understood that modifications in the construction and arrangement of the parts and in the character of the materials used may be adopted without departing from the spirit of the invention as set forth in the appended claim.

40 The invention in general comprises the provision of a railroad spike with a plurality of spaced grooves which are arranged in a manner simulating a spiral relation to each other so that as the spike is driven into the tie it will tend to turn and enter the tie after the manner of a screw. These grooves are preferably formed with upwardly facing shoulders which, as the spike is embedded in the wood of the tie, will be so related with respect to the wood as to resist any retractive movement of the spike. The 45 grooves are cut in the spike and each slopes downwardly and around the spike a given distance.

In the preferred form of the invention shown in the drawings there is represented a spike 1 having a head 2 and a point 3. A plurality of grooves are cut in this spike, each groove being formed, preferably, with an upwardly facing shoulder 4. The shoulder 4, as noticed particularly in Fig. 2, slopes downwardly and around the spike a given distance. The grooves may be lettered A, B, C, D and E. It will be noted that the topmost groove curves downwardly and around the spike a given distance and that the next groove, B, curves downwardly around the spike a similar distance and in the general direction that a continuous spiral curve would follow. A similar course is taken by the successive grooves C and D. It will be noted that the bottom groove E and another associated groove, such as F (see Fig. 2) have shoulders 5 which slope downwardly and around the groove. These shoulders, however, face downwardly and their slope is much greater than the slope of the previously mentioned shoulders 4.

The reason why the shoulders 5, formed by cutting grooves near the lower end of the spike, face downwardly, and the reason why their slope is much greater is so that as the spike is driven in these shoulders will act, in encountering the material of the tie, 50 to turn the spike as it advances into the tie, and by turning the spike will enter the tie without disrupting its material too much. By thus reducing the disruption or displacement of the material of the tie the 55 resistance to retraction of the spike will be much greater since the material of the tie immediately around the spike is more solid than would otherwise be the case, especially with respect to its ability to resist the removal of the spike by reason of its firm contact with the shoulder 4.

It will, therefore, be observed, in the general conception of the invention, that I have provided a simple and efficient spike which has formed on it two kinds of grooves. The 60 grooves extending from the top of the spike to a point near the bottom are provided with upwardly facing shoulders and their main purpose is to prevent the retraction of the spike, whereas the grooves formed at the 65 bottom of the spike are provided with downwardly facing shoulders and a much greater pitch and their main function is to cause the spike to turn as it enters the tie. It is also 70 obvious that these grooves may be cut in the 75

spike by machinery or by hand or may be formed in the process of casting or otherwise forming the spikes.

In Figs. 3 and 4 the spike has been modified by cutting one side of the head 3 off, as is usual in railroad spikes, so that excess material not necessary is eliminated.

What I claim is:—

A railroad spike, which comprises a body portion having a tie entering point and a plurality of spirally disposed grooves

throughout its length, each of said grooves provided with an upwardly facing shoulder whereby the retraction of the spike from the tie is resisted by said shoulder, said spike having a plurality of grooves adjacent the tie entering point provided with downwardly facing shoulders, the pitch of said last-mentioned grooves being much greater than the pitch of the first-mentioned grooves.

FRANK S. HARRINGTON.
